UNITED STATES PATENT OFFICE.

NATHANIEL S. BARGER, OF ST. JOSEPH, MISSOURI.

DUST-PROOF JOURNAL FOR CULTIVATOR-DISKS.

SPECIFICATION forming part of Letters Patent No. 758,582, dated April 26, 1904.

Original application filed May 18, 1903, Serial No. 157,567. Divided and this application filed October 15, 1903. Serial No. 177,107. (No model.)

To all whom it may concern:

Be it known that I, NATHANIEL S. BARGER, a citizen of the United States, residing in St. Joseph, county of Buchanan, State of Missouri, have invented certain new and useful Improvements in Dust-Proof Journals for Cultivator-Disks, of which the following is a specification, reference being had therein to the accompanying drawings, in which—

10 Figure 1 is a longitudinal vertical sectional view; Fig. 2, a side elevation, and Fig. 3 a vertical transverse sectional view taken on the line III III of Fig. 1.

15 The main object of this invention is to provide a simple, durable, and effective dust-proof journal for cultivator-disks; and it consists in the novel combination and arrangement of parts hereinafter described, and more particularly pointed out in the claims appended.

20 Referring to the various parts by numerals, 1 designates a cultivator-disk provided at its center with an aperture, in which is rigidly secured a hub 2. This hub is formed with a radial flange 3, which fits against the outer concave side of the disk and is riveted or otherwise rigidly secured thereto. A central longitudinal socket 4 is formed in the hub to receive the inner end of the spindle 5, said spindle being rigidly secured in the socket by means of a transverse bolt 6, which passes through that portion of the hub projecting beyond the convex side of the disk and through the inner end of the spindle. Fitting the spindle is a journal-box 7, preferably of wood, and on the outer end of the spindle is rigidly secured a dust-cap 8, which is formed with an inward-extending dust-excluding flange 9, said flange embracing the outer end of the journal-box and preventing dust or dirt entering between the journal-box and the spindle.

25 Embracing the upper side of the journal-box 7 is an arched bearing-block 10, this block being formed at its inner end with a laterally-extending flange 11, whose inner end extends beyond the joint between the hub and the journal-box and prevents dust and dirt entering said joint. The upper side of the bear-

ing-block is provided with a circular series of serrations 12, which are adapted to be engaged by a corresponding series of serrations formed on the end of a supporting-bar 13. To rigidly clamp the journal-box 7 to the bearing-block 11 and to the supporting-arm, I provide a vertical bolt 14, which passes through the arm and the bearing-block and is formed at its lower end into a ring or yoke 15, which surrounds the journal-box. At the point where this ring or yoke passes around the journal-box the bearing-block is cut out slightly to permit said yoke to be drawn up by the nut 16 to cause the journal-box to bind against the bearing-block on both sides of the yoke. It will thus be seen that the single bolt 14 clamps the journal-box to the bearing-block and also rigidly secures the bearing-block to the supporting-arm 13. By loosening the nut 16 the bearing-block may be adjusted to any desired angle with respect to the supporting-arm and then may be rigidly secured in its adjusted position.

30 From the foregoing it will be readily seen that I provide an exceedingly simple but durable dust-proof journal which may be readily adjusted to any desired angle. It will also be noted that when the wooden journal-box becomes worn or broken it may be readily removed and replaced by a new one by removing the cap 8 from the end of the spindle. This may be readily accomplished without disconnecting the disk from its supporting-arm.

35 Having thus described my invention, what I claim as new, and desire to secure by Letters Patent, is—

1. The combination of a cultivator-disk, a spindle secured rigidly at one of its ends to said disk, a journal-box loosely mounted on said spindle, a dust-cap secured rigidly to the free end of the spindle and embracing one end of the journal-box, a bearing-block embracing the upper part of the journal-box and formed with a dust-excluding flange covering the inner end of the journal-box, a supporting-arm and means for clamping together the journal-box, bearing-block and supporting-arm.
2. The combination of a cultivator-disk, a

- hub secured to the center thereof, a spindle rigidly secured in said hub, a journal-box loosely mounted on said spindle and abutting against the inner end of the hub a dust-cap 5 on the free end of the spindle and provided with a dust-excluding flange which covers the outer end of the journal-box, a bearing-block embracing the upper part of the journal-box and formed with a dust-excluding flange which 10 covers the joint between the hub and the journal-box, a supporting-arm and a clamping-yoke adapted to secure together the journal-box, bearing-block and supporting-arm.
3. The combination of a cultivator-disk, a hub secured to the center thereof, a spindle rigidly secured at one of its ends in said hub, a journal-box loosely mounted on said spindle, a dust-cap detachably secured to the outer end of the spindle and provided with a dust-excluding flange covering the outer end of the journal-box, a bearing-block embracing the upper part of the journal-box and provided with an inward-extending 15 20 25 30 35 40 45 50
- the joint between the journal-box and the hub, a supporting-arm, a ring-like clamping-yoke extending around the journal-box and formed with a threaded stem extending through the bearing-block and supporting-arm, and a nut screwed on the end of said stem whereby the journal-box and bearing-block may be clamped to the supporting-arm.

together the journal-box, bearing-block and supporting-arm.

4. The combination of a cultivator-disk, a hub secured to the center thereof, a spindle secured at one of its ends in said hub, a journal-box loosely mounted on said spindle, a dust-cap detachably secured to the outer end of the spindle and provided with an inward-extending annular dust-excluding flange embracing and covering the outer end of the journal-box, a bearing-block embracing the upper part of the journal-box and provided with an inward-extending dust-excluding flange covering the joint between the journal-box and the hub, a supporting-arm, a ring-like clamping-yoke extending around the journal-box and formed with a threaded stem extending through the bearing-block and supporting-arm, and a nut screwed on the end of said stem whereby the journal-box and bearing-block may be clamped to the supporting-arm.

In testimony whereof I hereunto affix my signature, in the presence of two witnesses, this 8th day of October, 1903.

NATHANIEL S. BARGER.
